FIG.4.

FIG.5.

FIG.8

FIG.9

FIGURE 1 is a side elevational view of a jug, showing my new design, wherein a bulge is formed on the inner portion of the handle members to serve as a finger grip or separation;

FIGURE 2 is an elevational view thereof taken from the right of FIGURE 1;

FIGURE 3 is a top plan view thereof;

FIGURE 4 is a side elevational view of my design for a jug shown in FIGURE 1 wherein a pair of bulges are formed on the inner portion of the handle to serve as finger grips and the upper inner portion is more rounded to accomodate an extra finger;

FIGURE 5 is an elevational view thereof as taken from the right of FIGURE 4;

FIGURE 6 is a cross-sectional view taken on lines 6—6 of FIGURE 1;

FIGURE 7 is a cross-sectional view taken on lines 7—7 of FIGURE 1;

FIGURE 8 is a cross-sectional view taken on lines 8—8 of FIGURE 4; and

FIGURE 9 is a cross-sectional view taken on lines 9—9 of FIGURE 4.

The characteristic features of my design consist of a jug having a central portion of the body slightly recessed with respect to the top and bottom portions, said recessed portion being further set off by contrasting bands at the top and bottom areas adjacent thereto, and in combination with the specific handle portion having shaped finger grips as shown in FIGURES 1 and 4.

I claim:

The ornamental design for a jug, substantially as shown and described.
